CORPORATION OF DELAWARE

LINING FOR MOLDS FOR CONCRETE COLUMNS

Application filed November 9, 1931. Serial No. 573,840.

This invention pertains to linings for holes formed in the ground to serve as molds for concrete columns.

Each hole is sunk to solid footing by any suitable means and is then filled with concrete to form the column. It is usually necessary to line the mold to prevent collapse of its walls prior to the pouring of the concrete. The lining is usually a steel or wooden shell, and it may either be withdrawn as the concrete is poured or it may be left in the hole to become a part of the column. In either case it is necessary for convenience in handling to form the shell in comparatively short sections which are joined together to compose the lining.

An object of the invention is to provide means for coupling the sections together with a minimum of time and effort.

Another object is to disclose a form of composite steel and wood lining readily formed on the job and having other favorable features which will be apparent to those skilled in the art.

Further and other objects and advantages will be apparent from the specification and claims, and from the accompanying drawings which illustrate what is now considered the preferred embodiment of the invention.

Fig. 1 is a sectional view of the steel skeleton of a section of the composite lining.

Fig. 2 is an end view of Fig. 1.

Fig. 3 is a view, partly broken away, of a completed section of composite lining.

Fig. 4 is an end view of Fig. 3.

Fig. 5 is a vertical section showing a composite lining in the hole in the ground, and with the hoisting device attached to the upper end of the lining.

Fig. 6 is a cross-section on line 6—6 of Fig. 5.

Fig. 7 is an enlarged detail of the arrangement for driving the composite shell.

Fig. 8 is an enlarged detail of a driving shoe on the bottom of the composite shell.

Fig. 9 is an enlarged detail of the coupling device for composite shell sections.

Fig. 10 is an enlarged detail view of a similar coupling device for steel shell sections.

As shown in Figs. 1 and 2 the skeleton for

a section of composite lining may comprise a number of similar circumferentially spaced longitudinal strips of flat steel 20, each with an outwardly turned hook 22 at one end. Surrounding bands 20 a short distance from hooks 22 is an angle iron ring 24 arranged substantially as shown. At the other end of strips 20 is a similar angle iron ring 26 arranged with one flange flush with the ends of strips 20. Spaced at equal intervals along the length of the skeleton are T-iron rings 28. Rings 24, 26 and 28 are all riveted to strips 20. The skeleton and shell are assembled on the job, all parts being delivered in knocked-down condition, thus effecting a great saving in freight and handling charges.

After a skeleton is formed as above, it is enclosed in wood staves 30, usually tongued-and-grooved, each stave being of proper length to fit between the projecting flanges of the circumferential rings of the skeleton. One successful method of performing the enclosing operation is to place the skeleton on rollers 32, then to fit staves 30 on the upper side of the skeleton, gradually rotating the structure until the enclosure is complete, as in Figs. 3 and 4.

As the staves are fitted into place, nails 34 (Fig. 5) may be driven through the rings into some of the staves to hold them in place, or, if desired, nails may be driven through the staves past the edges of the rings and then bent over the webs of the rings, as at 36 (Fig. 5). Circumferential strips 38 of band steel are nailed around the section when the staves are all in place, and the shell section is then ready for use. It will be noted that the section has no projecting parts. The interior presents no projections upon which the bucket may catch on its way up or down. In fact, strips 20 serve to guide the bucket and keep it out of contact with the staves.

For convenience in handling the shell or shell sections a hoisting device is provided, comprising a ring 40, spokes 42 and cables 44 attached to plates 46 riveted to ring 40. Ring 40 is similar to rings 24—26 of the shell skeleton; therefore when it is slipped over the projecting ends of strips 20 it is auto-

matically locked in position by hooks 22, which return to their normal positions after ring 40 has passed them (Figs. 5 and 9). The shell or shell section may then be suspended vertically from a crane hook engaging the upper ends of cable 44.

The lower end of the shell section first inserted in the hole is provided with an angle iron ring 45 secured to the end ring 26 of the skeleton, and arranged so that its depending flange will serve as to ream the sides 47 of the hole if any reaming is necessary. Reamer ring 45 may be stiffened by angle braces 48 welded in place, if desired.

In case the weight of the shell is insufficient to lower it into the hole, it may be forced down by pressure applied to the top of the shell, preferably through the instrumentality of a ring 50 (Fig. 7) of I-beam or channel steel of sufficient stiffness to distribute the pressure evenly around the shell.

If a single shell section is insufficient to line the hole, other sections are added until the required shell length is attained. Each section is coupled to the one below it by simply lowering it into place until ring 26 of one section slips past hooks 22 of the other section, whereupon the hooks will automatically engage the top of ring 26 and the sections will be locked together as indicated in Figs. 5 and 9. The coupling operation may be performed either above ground or in the hole.

Sections may be uncoupled by simply wedging out the hooks and then pulling the sections apart.

The automatic coupling device has been described as applied to a wood stave shell, but may be used in similar manner with steel shells, as shown in Fig. 10, in which shell sections 52—54 form a butt joint at 56, and in which hooks 58 fastened to one section and projecting beyond its end automatically engage a band 60 riveted onto the end of the other section. A spacer band 62 is usually placed between band 60 and the shell to which it is attached, in order to provide a space 64 to accomodate any irregularities in the contours of the abutting ends. The hooks and rings are shown on the insides of the shell, but may be on the outsides if desired. Ring 60 may project beyond the end of the shell section to which it is attached in order to more readily guide the other section into proper aligned position.

It is to be understood that the invention is not limited to the specific embodiment herein illustrated and described, but may be used in other ways without departure from its spirit as defined by the following claims.

We claim:

1. A section of a lining adapted to be placed in a hole in the ground to form a mold for a concrete column, comprising a steel skeleton having longitudinal circumferentially spaced

strips with external rings spaced longitudinally of said strips and attached thereto to provide an unobstructed interior for the lowering of the digging bucket, in combination with wooden staves between said rings whereby a tubular shell section is formed.

2. A section of a lining adapted to be placed in a hole in the ground to form a mold for a concrete column, comprising a steel skeleton having longitudinal circumferentially spaced strips with external rings spaced longitudinally of said strips and attached thereto to provide an unobstructed interior for the lowering of the digging bucket, in combination with wooden staves between said rings whereby a tubular shell section is formed, and hooks on the ends of said strips, said hooks being adapted to engage a ring on a similar shell section when the ends of said sections are placed in aligned contact.

3. A section of a lining adapted to be placed in a hole in the ground to form a mold for a concrete column, comprising a steel skeleton having longitudinal circumferentially spaced strips with external steel rings attached thereto and having outwardly projecting circumferential ribs said rings being equally spaced along said strips, in combination with wooden staves placed longitudinally between said ribs whereby a tubular shell section is formed.

4. The invention set forth in claim 3 in which said strips are provided at their ends with hooks adapted to engage the end ring of a similar shell section when the ends of said sections are placed in aligned contact.

5. A device of the class described, a wooden lining for a mold for a concrete column, in combination with longitudinal metal strips spaced around the interior of and away from said lining to produce a smooth uninterrupted interior for the passage and guidance of a digging bucket and keep it out of contact with said lining.

6. A section of a lining adapted to be placed in a hole in the ground to form a mold for a concrete column, comprising a steel skeleton having longitudinal circumferentially spaced strips with external rings spaced longitudinally of said strips and attached thereto, staves secured to said rings, hooks on the ends of said strips and a hoisting ring automatically engageable with said hooks.

7. A device of the class described, comprising a steel skeleton having longitudinal circumferentially spaced strips with rings spaced longitudinally of said strips and attached externally thereto to produce an uninterrupted interior for the passage of a digging bucket, and staves secured externally to the rings whereby a tubular shell section is formed.

8. A device of the class described, comprising a steel skeleton having longitudinal circumferentially spaced strips with rings spaced longitudinally of said strips and at-

- tached externally thereto to produce an uninterrupted interior for the passage of a digging bucket, staves secured externally to the rings whereby a tubular shell section is
5 formed, and hooks on the ends of said strips adapted to engage a ring on a similar shell section when the ends of said shell sections are placed in end to end contacting relationship.
- 10 9. A lining for a mold for concrete column, comprising a plurality of axially aligned shell sections, each including longitudinally disposed and circumferentially spaced strips, axially spaced rings secured to the outside
15 of said strips and having outwardly projecting flanges, staves secured to said rings between said flanges and spaced from said strips, said strips serving to guide a bucket into the hole which the mold lines and to prevent contact of said bucket with the staves or rings, and hooks on said strips adapted to enter a ring on a corresponding lining section when
20 said sections are placed in end to end contacting relationship.
